UNITED STATES PATENT OFFICE

ALBERT L. ARENBERG, OF CHICAGO, ILLINOIS

LAMP WITH SLIDING JOINT

Application filed May 22, 1930. Serial No. 454,722.

This invention relates to an improved indirect floor lamp and has for one of its principal objects the provision of a simple yet efficient lamp for indirect illumination which at the same time includes the advantages of portability as embodied in a floor or table lamp, and at the same time constitutes an attractive article of furniture.

This application constitutes a further development and an improved construction over my previous applications for patent on "shadowless portable lamps" and "shadowless portable lamp with shade", Serial Nos. 336,618 and 336,619 respectively, both filed January 31, 1929.

One of the important objects of this invention is the provision in an indirect portable lamp, having a conical type inverted reflector bowl, of means for removably supporting the reflector bowl on the base, said means embodying a sliding joint.

Another important object of this invention is the provision in an indirect lamp having an inverted reflector bowl and a shade mounted thereon, of additional lighting means mounted on the bowl for illuminating the shade.

Still other and further important objects of the invention reside in improved means for mounting the shade upon the reflector bowl, this mounting providing a secure yet removable positioning.

Other and further important objects of the invention will be apparent from the disclosures in the accompanying drawings and following specification.

The invention, in a preferred form, is illustrated in the drawings and hereinafter more fully described.

In the drawings:

Figure 1 is a vertical sectional view of the improved indirect lamp of this invention.

Figure 2 is a detail view illustrating a modified means of shade attachment.

Figure 3 is a top plan view of the shade attaching means shown in Figure 2.

Figure 4 shows another modification of the shade attaching means.

Figure 5 is a top plan view of the modification illustrated in Figure 4.

Figure 6 is a detail sectional view illustrating a modification of the connection between the reflector bowl and the base.

Figure 7 illustrates a still further modification of the attachment between the reflector bowl and the lamp socket body.

Figure 8 shows still another shade mounting.

As shown in the drawings:

The reference numeral 10 indicates generally a standard for a lamp which is preferably a portable lamp of either the floor or table type, the upper end of the standard having mounted thereon a body 12 adapted for the reception of a lamp socket 14, a switch cord 16 and various connecting wires 18 and 20.

The upper end of the body 12 is outwardly flared to form a collar 22, preferably integral therewith and shown in this instance as having parallel sides.

A reflector bowl 24 preferably composed of metal and formed in any convenient or desired shape, preferably somewhat conical as shown in Figure 1 is fitted into the collar 22, this fitting comprising a lower extension on the reflector bowl in the form of a rim which is of such dimensions as to securely yet slidably fit into the collar 22. The interior of the reflector bowl 24 is polished so as to direct light rays from the globe 26 upwardly and outwardly onto the walls and ceiling of the room in which the lamp is used, thereby providing for indirect illumination as set forth in my previously filed co-pending applications aforesaid.

A shade 28 which may be of any shape or size desired and which may include various ornamental features and may be composed of any suitable material is provided for the lamp, the shade as shown in Figure 1 being provided with an upper circular rim 30 which fits over the upper edge 32 of the reflector bowl 24 which is preferably fitted as shown.

In order to illuminate the interior of the shade, a plurality of additional sources of light 34 are provided, these being mounted on extending arms 36 fitted to the sides of the reflector bowl 24, removable connections 100

38 being provided between the wires 20 and corresponding wires in the arms 36, these removable connections passing through suitable openings in the sides of the reflector bowl 24. Obviously, any desired number of these additional sources of light may be used, each having an operating switch 40, so that the intensity of the light on the shade may be varied as desired.

10 In Figures 2 and 3 is illustrated a modified means of mounting the shade upon the upper edge of the reflector bowl 24, the shade in this case having an upper rim 42 slightly larger than the upper beaded edge 32 of the reflector bowl and with inwardly extending supports or the like 44 connected to the periphery thereof at three or four points spaced therearound.

20 In Figures 4 and 5 is illustrated a means for locking the shade in position on the reflector bowl, the bowl in this instance shown as provided with an outwardly flared collar 46 forming its upper rim and the upper edge 48 of the shade being provided with a plurality of inwardly extending bars 50 which support an inner ring 52, this ring 52 being in turn locked in position in the collar 46 by means of a plurality of spring clips 54 mounted at suitable intervals about the inner upper edge of the reflector bowl.

30 Figure 8 shows a shade 70 having an upper ring 72 connected by bars 74 to an inner ring 76 which rests on the upper edge of the reflector bowl, and is held in position by an annular collar 78 mounted beneath the bars 74 and adapted to slip over the rim of the reflector bowl.

40 In Figure 6, the reflector bowl 56 is shown as having an outwardly flared collar 58 for its lower rim, this collar being adapted to fit slidably over the correspondingly shaped upper edge 60 of a cluster body or the like similar to the body 12 shown in Figure 1.

45 In Figure 7 is illustrated a modification of the means for mounting a reflector bowl on the base or cluster body, the reflector bowl 62 in this instance being shown as provided with an integral lower rim 64, the same being turned inwardly so as to provide a wedge-shaped fit with a corresponding outwardly turned collar 66 formed integral with the upper edge of the cluster body or support 68.

55 It will be evident that herein is provided a lamp for indirect illuminating effects which in addition to providing a powerful source of light for illuminating the walls and ceiling of a room without casting any glare into the user's eyes, also provides an attractive lamp similar to the floor or table lamps now in use, the same having a shade thereon adapted to be illuminated from the interior thereof, and the source of shade illumination being sufficiently powerful to provide additional downwardly directed light rays for the use of a person seated directly beneath

the lamp, if such illumination is found desirable.

60 I am aware that many changes may be made and numerous details of construction varied throughout a wide range without departing from the principles of this invention, and I, therefore, do not purpose limiting the patent granted hereon otherwise than as necessitated by the prior art.

75 I claim as my invention:

70 In an indirect lamp, the combination of a base and a removable reflector, a sliding joint between the base and the reflector, said sliding joint comprising an integral collar at the lower end of the reflector and an annular extension on the base fitting into said collar, a source of light inside the reflector and other sources of light outside the reflector and mounted thereon, together with a shade surrounding said reflector and lights, 80 said shade mounted on and supported by said reflector, the supports for the shade comprising resilient inwardly extending clips mounted in the shade and adapted to be fitted over the upper rim of the bowl, and detachable current carrying connections for the outside lights.

85 90 In testimony whereof I affix my signature.

95 ALBERT L. ARENBERG.
